UNITED STATES PATENT OFFICE

2,180,014

SOUND MOTION PICTURE REPRODUCING APPARATUS

Richard S. Morse, Rochester, N. Y., assignor to
Eastman Kodak Company, Rochester, N. Y., a
corporation of New Jersey

Application October 23, 1936, Serial No. 107,254

3 Claims. (Cl. 179—100.3)

This invention relates to the reproduction of sound. More particularly it relates to the reproduction of sound in connection with motion pictures.

5 During the projection of motion pictures, it is sometimes desirable to describe verbally to the audience some particular feature, especially in the case of public speakers who illustrate or supplement their lectures by means of motion pictures (either silent or sound). If a sound motion picture projector is used to project silent films, it would be decidedly advantageous to allow the speaker to address his audience through the amplifying circuit and the loud speaker of the projector system. Even when sound films are being projected, occasions arise when it is desirable to interrupt the normal output of the sound record and to substitute pertinent comments or special announcements.

20 Obviously, to avoid confusion, the normal sound sequence should be silenced during the interlocution. Depending on the circumstances, it may or may not also be desirable, at that time, to interrupt the pictures, or to project a "still" 25 from a single frame.

It is an object of this invention to provide a method and means which will permit the output of an auxiliary microphone to utilize the amplifier and loud speaker of a sound motion picture projector.

30 It is a particular object of this invention to arrange an electrical circuit whereby the normal sound reproduction is interrupted when the auxiliary microphone circuit is completed. The 35 simultaneous interruption of the motion pictures (e. g., to project a "still") when desirable may easily be controlled by the operator of the projector or by any suitable remote control.

As pointed out above, this invention will be 40 particularly useful when motion pictures of the silent type are being projected by a sound projector.

Further objects and advantages of this invention will be apparent from the following description when read in connection with the accompanying drawing in which:

Figure 1 shows one particular form which the invention may take.

Figures 2 and 3 schematically show the construction of two mechanisms suitable for use as switch 10, Figure 1.

Figure 4 shows an alternative switching arrangement which may be used as described below in a modified form of the circuit shown in Figure 1.

In Figure 1, a motion picture film 13 bearing a sound track 12 is moved in a well known manner between a projection lamp 28 and a projection lens 29 to project the pictures in the usual way. The film band 13 is also moved so that the sound track 12 modulates the light from an exciter lamp 11. The modulated beam of light is received by a photoelectric cell 14 which with its accompanying circuit and loud speaker transforms the modulated luminous energy into modulated electrical energy, and finally into audible sound in the well-known manner. In the circuit, the alternating component of the output of the photoelectric cell 14 is transmitted through a condenser 15 to the grid of a thermionic amplifier tube 16. The potential for the photoelectric cell 14 is supplied from a source 19 through resistances 17 and 18. An electrical switch 20 comprising electrodes 21, 22, 23, and 24 is connected, as shown, in the grid circuit of the tube 20 16 in series with a grid leak resistance 26. An auxiliary microphone 25 is connected between ground and the electrode 24 of the switch 20.

In normal operating position, the switch 20 is set so that electrodes 22 and 23 are in contact, and electrodes 21 and 24 are entirely disconnected. Thus, the power from the source 19 is supplied to the photoelectric cell 14, the grid leak 26 is connected directly to ground and the auxiliary microphone 25 is disconnected from the 30 circuit.

The switch 20 is arranged so that it has only one alternative position. In this alternative position, the electrodes 21 and 22 are connected and the electrodes 23 and 24 are connected. 35 Thus, the source of potential 19 is shorted, the resistance 18 being provided to prevent any damage being done thereby. Also, the grid leak 26 is no longer directly connected to ground, but is in series with the microphone 25.

Hence, the output of the microphone 25 is substituted for the output of the photoelectric cell 14 and is supplied to the grid of the tube 16, the output of which in turn operates an amplifier and loud speaker system 27.

45 This switch 20 may be designed in various ways. Two satisfactory and convenient arrangements are shown in Figures 2 and 3.

In Figure 2, the electrodes 21 and 23 are mounted rigidly on a base 31. The electrodes 22 and 50 24 are rigidly connected by a member 32 which is pivotally mounted on the base 31. A spring 34 mounted on the base 31 holds the member 32 so that the electrodes 22 and 23 are normally in contact. Pressure exerted on a button 33 which 55

is mounted on the member 32 compresses the spring 34 to disconnect electrodes 22 and 23, and to connect electrodes 23 and 24 and electrodes 21 and 22, respectively as discussed above.

5 Figure 3 shows a jack type connector adapted to operate as the switch 20. A plug 36 carries electrodes 24 and 37 which are connected to the microphone 25. The plug 36 may be inserted between spring members which comprise the 10 electrodes 22 and 23. Normally the electrodes 22 and 23 are in contact as shown. When the plug 36 is inserted, electrodes 22 and 23 are separated and electrode 22 is moved into contact with electrode 21. Insertion of the plug 36 also brings 15 the electrodes 23 and 24 and the electrodes 22 and 31 into contact to connect the microphone 25 between the grid leak resistance 26 and ground as described in connection with Figure 1.

Referring back to Figure 1, the sound track 20 12 may be carried on the film as shown or it may be of the sound-on-disk type. If it is of the sound-on-film type, it may be either variable width or variable density. The circuit used with the photocell 14 may be of any suitable 25 type, only one of which is shown. The introduction of the microphone 25 into the circuit and the interruption of the audio output of the photoelectric cell 14 may be accomplished in a number of ways. For example, the exciter lamp 11 30 may be extinguished during the interlocution instead of shorting the potential source 19.

One suitable form of switch for accomplishing this is shown schematically in Figure 4. Electrode 21 has been eliminated in this case and 35 two electrodes 41 and 42 have been introduced. These latter two electrodes are connected in series with the exciter lamp 11 and act as a switch therefor. In normal operating position electrodes 22 and 23 and electrodes 41 and 42 40 are in contact. When the switch is actuated to connect the microphone in the circuit it opens the ground connection at contacts 22 and 23 and separates the contacts 41 and 42 to open the exciter lamp circuit. Thus the exciter lamp 45 is extinguished, the photoelectric cell 14 is darkened, and the tube 16 receives only the output of the microphone 25.

In Figure 1, the tube 16, shown as a triode, is merely to represent suitable means for receiving and transmitting the modulated electrical 50 energy from the alternative sources. Other

satisfactory arrangements will immediately suggest themselves to those skilled in the art.

Having thus described this invention, I wish to point out that it is not limited to the specific forms shown but includes those modifications falling within the scope of the appended claims. 5

I claim:

1. In a system for reproducing sound from a photographic sound record, a photo-cell the illumination of which is controlled by said record, an amplifier including a vacuum tube provided with a grid, means including a grid leak resistance for impressing potential variations upon the grid corresponding to the illumination of said cell, a microphone, and switching means operative to 10 disconnect said means and to connect the microphone in series relation with said grid resistance, whereby the microphone is in circuit to control the input to said amplifier. 15

2. In a system for reproducing sound from a photographic record having variations characteristic of the sound recorded thereon, means for transforming the sound record variations into electrical current variations, said transforming means consisting of a photoelectric cell and a 20 source of potential therefor, means for translating the electric current variations into potential variations, an amplifier connected to said translating means, means for side tracking the power of said source of potential away from the photoelectric cell, a microphone, and a two position switch so arranged that in one position the source of potential is disconnected from the side tracking means and the transforming means is connected to the translating means, and in the 25 other position the source of potential is connected to the side tracking means and the microphone is connected to the translating means. 30

3. Apparatus for the reproduction of sound motion pictures comprising a motion picture film bearing an optical sound record, an exciter lamp to illuminate said sound record, a loud speaker, a photoelectric cell arranged to receive light modulated by said sound record and connected to operate the loud speaker through a suitable electrical circuit, a microphone and means movable to extinguish said exciter lamp thereby rendering said photoelectric cell inoperative and to connect said microphone to the loud speaker circuit. 40
